FIG. 3.

FIG. 4.

Inventor

Lawrence J. Tracy

UNITED STATES PATENT OFFICE.

LAURENCE J. TRACY, OF ST. LOUIS, MISSOURI; JENNIE O'LEARY, BEING ADMINISTRATRIX OF SAID LAURENCE J. TRACY, DECEASED, ASSIGNOR, BY DIRECT AND MESNE ASSIGNMENTS, OF ONE-FOURTH TO WALTER L. DEERING, OF ST. LOUIS, MISSOURI, ONE-FOURTH, TO CHARLES J. GEVECKER AND HARRY GEVECKER, ONE-TENTH TO MARY CONNELL, ONE-TENTH TO MARGARET DECKER, ONE-TENTH TO REBECA McGRANE, ONE-TENTH TO JENNIE O'LEARY, AND ONE-TENTH TO JAMES TRACY.

ELECTRIC HEATER.

1,417,427.

Specification of Letters Patent. Patented May 23, 1922.

Application filed March 11, 1921. Serial No. 451,616.

To all whom it may concern:

Be it known that I, LAURENCE J. TRACY, a citizen of the United States, and resident of St. Louis, Missouri, have invented certain new and useful Improvements in Electric Heaters, of which the following is a specification.

This invention relates to improvements in electric heaters, and has for its object a heater comprising an outer shell, a drum located in said shell, and suitably spaced apart, a plurality of air circulating flues passing through the drum, and a heating element located in the drum by which the air is heated during its circulation through the flues.

A further object of my invention is to construct a heater which is both efficient as a heater as well as ornamental and the essential feature is to heat the air as it circulates through the same.

The heating unit consists preferably of one or a number of electric coils and so wired as to be operated independently or collectively and an indicator light wired to the coil to indicate the operativeness of the heating unit.

Figure 1, is a vertical sectional view of my improved heater.

Fig. 2, is a top plan view of the same with the lid or cover removed.

Fig. 3, is a horizontal sectional view taken on the line 3—3 of Fig. 1.

Fig. 4, is a diagrammatic view of the heating unit and its circuit.

In the general construction of my improved heater I provide an outer shell 5, at the bottom of which is located a flange or shield 6, and on the top of the shell is located a lid or cover 7, the same being constructed of a grille work or the like so as to provide free passage for the circulation and outlet of the heated air.

Inside of the shell 5 and suitably spaced from the same is a drum 8, the same having a bottom 9 and a top 10, both top and bottom is provided with a plurality of holes in which is firmly fixed the ends of pipes 11, which act as air circulating flues, per-

mitting the air to circulate from the bottom 50 of the heater through the flues and out through the ornamental top.

In the center of the drum is located a heating unit consisting of electric coils 12 by which the heat in the drum is generated 55 and as the coils become thoroughly heated the air is set in circulation and permitted to pass upwardly through the various flues and during such circulation becomes heated.

The bottom near the center is provided 60 with a plurality of apertures 13 which admit air into the interior of the drum, said air coming in direct contact with the heating unit. This air then passes out through openings 14 formed around the upper periphery 65 of said drum and is discharged into the passage 15 formed between the drum and the outer shell.

Through this passage air is also permitted to circulate and intermingle with the heated 70 air passing out through the openings 14, at the same time keeping the outer shell comparatively cool so that the heater may be conveniently handled.

The heater is supported on suitable stands 16 of any desirable construction and the same are of such height as to provide sufficient space between the floor line and the bottom 17 of the shield 6.

On the top of the cover is placed a suitable 80 ornamentation 18 in which is an electric lamp 19, the same being electrically connected to one of the coils comprising the heating unit.

Referring to Fig. 4, the diagrammatic 85 view, I illustrate the circuit for controlling the heating unit, in this instance two coils are shown "a" and "b". The coil "a" is connected to the wire "c" and the wire "d", the same connected to a plug "e" which 90 may be inserted in any convenient socket. The coil "b" has its one end connected by means of the wire "f" to the wire "c", the other end to a wire "g" to a switch "h" and from the switch by a wire "i" to a 95 plug "e".

By this arrangement either one or both of the coils may be operated either independ-

ently or collectively. Should all of the coils be in operation and the heat become too excessive, the coil "b" may be cut out by the operation of the switch "h" thus leaving 5 only one coil in operation. The lamp 19 which is on top of the cover is connected by means of the wires "j" and "k" to the lower coil as illustrated. This light is at all times illuminated while the coil is in operation; 10 thus this lamp acts as an indicator to show the coil is in operation as well as an ornament in the room, also indicating the location of the heater especially when entering a dark un-illuminated room.

15 The wires which lead from the coil are conveniently placed as that indicated by the numeral 20.

Having fully described my invention what I claim is:

20 1. An electric heater comprising an outer shell, a drum located in the outer shell and suitably spaced therefrom, a plurality of air circulating flues passing through said drum and a heating unit located centrally in said 25 drum, substantially as specified.

2. A heater of the character described comprising a shell, a shield located at the bottom of said shell, a drum located inside of the shell and suitably spaced therefrom, 30 a plurality of flues passing through said drum, openings formed in the bottom of the drum and located near the center and openings formed on the periphery near the top of said drum, an ornamental cover placed on 35 the top of the shell, a heating coil positioned in the drum and a light located on the cover.

and in circuit with the coil, substantially as specified.

3. A heater of the class described comprising a shell, a drum located therein, said drum having a top and a bottom, flues passing through the drum and supported by the top and bottom, the upper end of the drum having its periphery provided with outlet openings, the bottom provided with openings for the admission of air into the drum and to be in direct communication with the heating unit and ornamental open cover located on the top of the shell, an electric heat unit placed in the drum for heating 50 the air as it circulates through the drum, substantially as specified.

4. A device of the character described comprising a heater consisting of an outer shell, a drum located in the same and suitably spaced from the outer shell, said drum having two end heads, flues supported by the end heads and passing through the drum providing air circulating passages, a sectional heating coil located in the drum and 55 so wired as to be operated separately and collectively and an independent light in connection with said coil, substantially as specified.

In testimony whereof, I have signed my 60 name to this specification, in presence of two subscribing witnesses.

LAURENCE J. TRACY.
